UNITED STATES PATENT OFFICE.

W. H. GWYNNE, OF WHITE PLAINS, NEW YORK.

IMPROVEMENT IN THE MANUFACTURE OF ILLUMINATING-GAS.

Specification forming part of Letters Patent No. 36,002, dated July 29, 1862.

To all whom it may concern:

Be it known that J. W. H. GWYNNE, of White Plains, in the county of Westchester and State of New York, have invented a new and useful Improvement in the Manufacture of Illuminating-Gas; and I do hereby declare that the following is a full, clear, and exact description of the same, reference being had to the accompanying drawings, making a part of this specification, in which—

Figure 1 represents a longitudinal vertical section of this invention, the line xx , Fig. 2, indicating the plane of section. Fig. 2 is a transverse vertical section of the same taken in the plane indicated by the line yy , Fig. 1.

Similar letters of reference in both views indicate corresponding parts.

This invention consists in introducing into a heated retort filled with coal, wood, or other material from which illuminating-gas can be manufactured, a stream of petroleum or rock oil, in such a manner that by the action of the petroleum the quality of the gas for the purpose of illumination is improved, and a rich gas can be produced from the poorest kind of coal or wood or other material, which, under ordinary circumstances, would hardly be fit for the manufacture of illuminating-gas.

To enable those skilled in the art to make and use my invention, I will proceed to describe its construction and operation with reference to the drawings.

A represents a retort of the ordinary construction, made of cast-iron or any other suitable material, and provided with a mouth-piece, B, and stand-pipe C. This retort is filled with coal, wood, or other material from which illuminating-gas can be manufactured, and when the same, together with its charge,

is heated to a bright-red heat a stream of petroleum or rock oil is introduced through a pipe, D. Said pipe enters through the side of the mouth-piece of the retort close down to its bottom, and it extends back nearly through the entire length of the retort. Outside the retort it is bent in the form of a siphon, to prevent the gas escaping from the interior of the retort, and it rises up to a funnel-shaped mouth-piece, a, through which the petroleum may be conveniently introduced, or it may be made to communicate directly with a tank, the flow of the liquid being regulated by a suitable stop-cock.

The petroleum is discharged from the pipe on the coal or wood or other material in the retort, saturates the same, and the gas produced in this manner is rich and of great illuminating power.

By the aid of this improvement poor coal or sawdust, or other material, which is generally considered unfit for the manufacture of illuminating-gas, or which, when used, produces gas of very inferior quality, can be used with advantage, and very rich and good gas obtained.

Having thus fully described my invention, what I claim as new, and desire to secure by Letters Patent, is—

Introducing into a retort containing coal, wood, or other material from which gas can be manufactured a stream of petroleum or other liquid hydrocarbons, substantially in the manner and for the purpose described.

W. H. GWYNNE.
